(57) **CLAIM**

The ornamental design for a bottle, as shown and described.

DESCRIPTION

The disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a top perspective view of a bottle according to our design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The dash-dash lines throughout the figures illustrate portions of the bottle that form no part of the claimed design. The dot-dash lines in the drawings define the bounds of the claimed design and form no part thereof.
